US0D1053837S

(12) **United States Design Patent** (10) **Patent No.:** **US D1,053,837 S**
(45) **Date of Patent:** **** Dec. 10, 2024**

(54) **SERVO AMPLIFIER**

- (71) Applicant: **Panasonic Intellectual Property Management Co., Ltd.**, Osaka (JP)
- (72) Inventors: **Takashi Koyama**, Kanagawa (JP); **Yusuke Shimogaki**, Osaka (JP); **Shota Tsukada**, Osaka (JP)
- (73) Assignee: **Panasonic Intellectual Property Management Co., Ltd.**, Osaka (JP)
- (**) Term: **15 Years**
- (21) Appl. No.: **29/913,282**
- (22) Filed: **Sep. 28, 2023**
Related U.S. Application Data
- (62) Division of application No. 29/699,786, filed on Jul. 29, 2019.

(57) **CLAIM**

The ornamental design for a servo amplifier, as shown and described.

DESCRIPTION

FIG. 1 is a front perspective view of a servo amplifier of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the drawings represent portions of the servo amplifier that form no part of the claimed design.
